M. G. HUBBARD.
Mowing Machine.

No. 19,298.

Patented Feb. 9, 1858.

UNITED STATES PATENT OFFICE.

M. G. HUBBARD, OF PENN YAN, NEW YORK.

IMPROVEMENT IN HARVESTERS.

Specification forming part of Letters Patent No. 19,298, dated February 9, 1858.

To all whom it may concern:

Be it known that I, M. G. HUBBARD, of Penn Yan, Yates county, and State of New York, have invented certain new and useful Improvements in Mowing-Machines; and I do hereby declare the following to be a clear and full description thereof, reference being had to the accompanying drawings, in which—

Figure 1 illustrates my improvements herein described; and the outline Fig. 2 illustrates the arrangement of parts which I have heretofore used and the defects of which my new arrangement and combination of parts are intended to remove or obviate.

These improvements consist of a new arrangement of some of the details of my two-wheeled mowing-machine, and are intended to improve its construction and operation.

It seems necessary that a machine for cutting grass should be supported on two large wheels, in order that the weight of the machine and driver may be moved easily, and so arranged as to equalize the draft and draw straight and true upon the team; and I have also found it necessary that the cutting apparatus should be independent of the machine to such a degree as to permit either end or both ends of the cutting apparatus to rise or fall and conform to the undulations of the ground. These objects are best accomplished by sustaining the frame on two large wheels and attaching the cutting apparatus to the frame by two heavy springs, substantially as described in the patent issued to me bearing date the 27th day of January, 1857.

In arranging the practical details of this machine it has been necessary in almost every feature to devise new elements in order more fully to develop the great utility of its general plan, and further experience has directed my attention to a necessary change in the construction and location of the inner shoe and the attachment of the right-hand spring to the cutting apparatus, &c.

In my experiments with this machine thus far I have attached the inner shoe to the inner end of the finger-bar, and then attached the rear end of the right-hand spring to this shoe and attached the front end of the said spring to the front of the main frame. By reference to the outline, Fig. 2, it will be seen that this arrangement brought one cutter directly be-

hind the supporting-wheel, and therefore one cutter was wasted, and the inner end of the cutter-bar was also brought so much nearer to the crank, and therefore compelled me to make the pitman so much shorter, which was a material disadvantage.

My new arrangement consists in locating the said shoe (marked O in Fig. 1) directly behind the supporting-wheel P, so that it will run directly in the path of the said wheel, and therefore require but a slight inclination upward to pass over the grass or other obstacles which have been compressed into a solid path by the said wheel in rolling over them. I extend the finger-bar sufficiently beyond this shoe to attach the rear end of the right-hand spring directly and firmly to the finger-bar. By this arrangement of the spring and location of the inner shoe I avoid wasting one cutter and finger behind the supporting-wheel, and also am enabled to make the pitman so much longer, which is very desirable. I also accomplish another important object in the perfect protection of the said spring from becoming weakened by wear, and as so much depends upon this spring in holding the cutting apparatus in place, it is highly necessary that it should be protected. In order to do this I make the shoe considerably thicker than the spring and place it close alongside of the spring, which keeps the spring up off from the ground; and to protect it still more perfectly I attach a thick wear-plate, *w*, under the spring, which evidently tends greatly to its preservation and adds to the durability of the parts, and as this wear-plate may be cast directly on the side of the shoe, and thus both of them being cast and fitted up at once, it is cheaper than the cutter and finger, which were wasted in the previous arrangement.

In order to prevent loose spears of grass from falling and gathering in between the elevated front end of the shoe and the spring, I extend a lip from the front end of the shoe down to and bend it entirely under the edge of the spring, giving the said lip an inclination forward, as seen at R, so that a spear of grass, in falling over onto the spring, may slide up and pass over and off from the spring or under the shoe. This entirely prevents any loose grass from accumulating between the shoe and spring, and enables me to locate them near

each other, so as to make as little bearing-surface on the ground as possible, and to give the front end of the shoe an upward curve for the purpose above referred to.

As it is necessary to clear a "track" at the outer end of the cutting apparatus, so that in cutting the next swath the inner shoe (and the projecting end of the finger-bar to which the spring is attached) will slide on the ground, in order to avoid raising the cutters too high by the shoe, &c., riding over cut grass, it might at first thought be supposed that by extending the finger-bar out beyond the inner shoe for the attachment of the spring, as described, I would unnecessarily increase the bearing-surface at the inner end of the finger-bar, and therefore require an increased width of track to be cleared by the "track-clearer," which would be objectionable; but it will be observed that the supporting-wheel could not be driven into the standing grass, and therefore, with either position of the inner shoe, a track would have to be cleared as wide as the spring and the tread of the wheel, because the spring must be located at the side of the wheel. Therefore my new arrangement of the spring and location of the shoe would require no wider track to be cleared by the track-clearer than was necessary for the previous arrangement of the shoe and wheel, as shown in Fig. 2. It is evident, however, that the use of the supporting-wheel and the spring passing down by the side of it renders it necessary to clear a wider track than would be required in the use of the arrangement of the shoe and spring shown at Fig. 2, if that arrangement should be used without the supporting-wheel in front of the inner cutter, and for the same reason it is evident that my new combination of parts requires a track considerably wider than is necessary in the use of some other mowing-machines. For some time I experienced great difficulty in overcoming this apparent obstacle, because in my early experiments with this two-wheeled machine I used the ordinary straight track-clearer hinged to the outer end of the cutting apparatus, and in order to clear a track sufficiently wide I had to make the clearer of an inconvenient length, or else set it at so great an angle as to cause it in many cases to operate imperfectly; but further experience developed a

more perfect principle upon which to construct a track-clearer, for which I received a patent dated the 20th day of January, 1857. I found that by making this track-clearer in the form of a curve, instead of placing it at an angle, its operation was much more perfect, and that I could clear a much wider track thereby. This discovery overcame the obstacle above alluded to, and enables me to use the arrangement of the spring and shoe and the supporting-wheel as described, and thereby attain all of the advantages above enumerated, and also overcome the most serious objections to their use.

In order to keep the inner shoe more firmly in position in the track of the supporting-wheel, I employ the lateral brace T, extending from the frame to the finger-bar; but I find it desirable, in order to adjust the position of the said shoe with accuracy and at the same time avoid the necessity of too great perfection in the construction of the parts of the cutting-apparatus, to make the length of the said lateral brace adjustable. To accomplish this I make several holes in the end of the lateral brace, as seen at *v v v v*, so that the pin *w²* can be altered to either of them; or the end of the said brace may be formed into a head and the brace screwed therein, so as to alter its length thereby. This arrangement enables me, without any great degree of accuracy in the construction of the parts, to readily adjust the position of the inner shoe so that it will run directly in the path of the supporting-wheel, and consequently require but a slight elevation of its front end to pass freely over cut grass or other obstacles which the supporting-wheel has previously compressed into a solid path by rolling over them, as above described.

Having thus fully described my improvements in mowing-machines, what I claim therein as new, and for which I desire to secure Letters Patent, is—

The attachment of the spring directly to the finger-bar, and placing the shoe on one side thereof and directly in the track of the supporting-wheel, as herein specifically set forth.

M. G. HUBBARD.
